UNITED STATES PATENT OFFICE

130,036

DESIGN FOR AN ESCUTCHEON PLATE FOR
AUTOMOBILE RADIO SETS OR THE LIKEClarence W. Wandrey, Elmwood Park, Ill., as-
signor to Zenith Radio Corporation, Chicago,
Ill., a corporation of Illinois

Application July 21, 1941, Serial No. 102,335

Term of patent 14 years

To all whom it may concern:

Be it known that I, Clarence W. Wandrey, a citizen of the United States, residing at Elmwood Park, in the county of Cook and State of Illinois, have invented a new original, and ornamental Design for an Escutcheon Plate for Automobile Radio Sets or the like, of which the following is a specification, reference being had to the accompanying drawing, forming part thereof.

Figure 1 is a perspective view of an escutcheon plate for automobile radio sets, showing my new design, and

Figure 2 is a vertical sectional view of the escutcheon plate taken upon line 2—2 of Figure 1.

I claim:

The ornamental design for an escutcheon plate for automobile radio sets or the like, as shown.

CLARENCE W. WANDREY.
